W. P. SCHLINGER

ELEVATOR

Filed June 16, 1923

Inventor

William P. Schlinger.

By Lyudmila

UNITED STATES PATENT OFFICE.

WILLIAM P. SCHLINGER, OF OXNARD, CALIFORNIA.

ELEVATOR.

Application filed June 16, 1923. Serial No. 645,804.

To all whom it may concern:

Be it known that I, WILLIAM P. SCHLINGER, a citizen of the United States, residing at Oxnard, in the county of Ventura and State of California, have invented a new and useful Elevator, of which the following is a specification.

This invention relates to a class of devices employed in the well drilling art for gripping certain parts such as the casing or sucker rod so that the same may be elevated or lowered in order to connect or disconnect their sections, such devices being commonly known as elevators; and this invention refers particularly to an elevator intended to handle sucker rods, although it is not the intention to limit this invention to its embodiment as a sucker rod elevator.

The primary object of this invention is to provide an elevator which upon engagement with a sucker rod or similar member will automatically lock the sucker rod in the elevator, and to provide such locking mechanism for the elevator which may be readily released from the elevator so that the sucker rod may be rapidly removed from the elevator, and upon the removal of the sucker rod will force the locking or latching mechanism thereof into the position proper for again engaging another section of the rod.

The elevators heretofore provided for sucker rods or the like have either required a manually operated locking mechanism which must be inserted in place after the elevator grips the rod, or the locking device has been difficult to unlock so that the rod may be removed from the elevator, and one of the principal objects and advantages of this invention resides in the ease and rapidity with which the elevator may be locked to and disconnected from a sucker rod.

Another object of this invention is to provide an elevator which is of durable and economical construction and retains the advantages heretofore set forth.

The objects and advantages of this invention will be apparent from the description hereinafter contained and will present themselves in the practice of the same. This invention includes certain novel combinations and association of parts, all of which will be apparent from the drawings and description.

In the accompanying drawings the preferred embodiment of the invention is set forth, and the invention is shown as embodied in the sucker rod elevator. Various modifications may be made in the device hereinafter described without departing from the spirit of the invention, and this invention is not limited to its use as a sucker rod elevator or to the specific construction or details of parts hereafter described.

The invention is of the scope set forth in the appended claims.

In the drawings:

Figure 1 is a front elevation of this embodiment of the invention with the member or link employed for suspending the elevator broken away.

Fig. 2 is a vertical section on the line 2—2 of Figure 1.

Fig. 3 is a plan view of the elevator with the suspension member or link removed and with the latching mechanism in the open position.

Fig. 4 is a plan view similar to Figure 3 with the latching mechanism in the closed position.

Fig. 5 is a section on the line 5—5 of Figure 3.

Referring to the drawings, 1 indicates the body of the elevator which provides two opposed trunnions 2 by which the elevator is connected to a suspension member 3'. Said member 3' may be either a single link or double links or any other preferred member for suspending the elevator. The trunnions 2 are preferably axially alined, the axis of the trunnions preferably extending through the center, or substantially through the center, of gravity of the elevator.

The body 1 of the elevator provides a rod receiving way 3 preferably extending at right angles from the axis of the trunnions 2 and shaped to closely fit the rod or casing to be held by the elevator. The rod-receiving way 3 preferably terminates in a cylindrical wall 3^a placed so that when the sucker rod is forced into the elevator and against the end wall 3^a of its receiving way, it will be held in substantially the center of the elevator and in alinement with the axis of the trunnions 2.

The top of the body 1 is recessed, as indicated at 5, to accommodate a member 4 which operates as a closure for the rod-receiving

way 3. Said member is preferably pivotally mounted on a vertical pin or screw 6 which is alined with the axis of the trunnions 2, the member or closure 4 being substantially 5 equal in height to the depth of the recess 5 in the body 1, so that the top of said member or closure 4 extends flush with the top of the body 1. The member 4 is mainly of 10 U-shape having two arms 7 and 8 which define a rod-receiving way 9 substantially equal in width to the rod receiving way 3 and extending laterally from the pin or screw 6 mounting the member 4 so that in the closed position the receiving way 9 intersects the 15 receiving way 3 at right angles, and in the open position said receiving way extends diagonal to the receiving way 3. The arm 7 thus serves as a door for the receiving way 3. The outer edge of said arm is preferably 20 shaped to engage the inner wall of the recess 5 when in the open position, as indicated in Figure 3, and the end of the arm 7 is cut away substantially flush with said receiving way 3 when in the position indicated in Figure 25 3. The arm 8 in the open position extends diagonally across the receiving way 3 and in position to be engaged by a sucker rod or the like when the same is forced into the elevator and rotate the closure 4 into the 30 closed position indicated in Figure 4.

The recess 5 of the body extends to the rear of the closure 4 and terminates in a guide way 10 extending parallel to the rod-receiving way 3. Said guide way 10 mounts 35 a latch control member 11. The latch control member 11 is rectangular in shape. The rear end 26 of the member 11 is bent slightly downward, as indicated in Figure 2, to provide a handle for operating the member, the 40 under portion 27 of said end 26 being cut away. 28 indicates a rectangular opening in the forward end of the control member 11, which slidably engages a vertically extending lug 13 of the body 1. Said lug 13 provides a vertically disposed opening in which 45 is guided a dog 15 extending parallel to the rod-receiving way 3 and through an opening 16 in a front wall 18 of the latch controlling member 11. A pin 19 extends transversely 50 through the dog 15 between the front wall 18 of the control member 11 and the lug 13. A spring 20 is coiled around the dog 15 abutting said pin 19 and lug 13.

21 indicates a small depression in the 55 closure 4 which engages the dog 15 in the open position, as indicated in Figure 3, thus the closure is yieldingly maintained in the open position. The depression 21 is preferably of insufficient depth to permit the dog 15 to have a locking engagement with the member 4 so that a pressure on the arm 8 may disengage the dog 15 from the depression 21 and rotate the closure 4 into the position indicated in Figure 4. In such position the dog 15 engages a recess 22 in the arm

8 of sufficient depth to provide a locking engagement between the arm 8 and dog 15 to thereby lock the closure 4 across the rod receiving way 3. The dog 15 may then be released from the closure 4 by a pull on the rear end 26 of the controlling member 11. By drawing said member 11 to the rear of the elevator, the front wall 18 will engage the pin 19 extending through the dog 15 and thus withdraw the dog 15 from the opening 22. In this position the sucker rod or similar device gripped in the elevator may be pulled away from the elevator through the rod-receiving way 3 and as the rod is withdrawn from the elevator, the same will engage the arm 7 of the closure 4 and rotate the same into the open position.

23 indicates a plate which rests upon the top of the elevator and is held in place by screws 24 inserted into the body 1. Said plate is provided with a rod-receiving way 25 complementary to the rod-receiving way 3 of the body 1.

It will be seen that by this construction the closure 4 of the elevator may be yieldingly maintained in the open position, as indicated in Figure 3, and when engaged with a sucker rod the closure 4 will automatically be rotated into the closed position and locked in place, thus preventing the sucker rod from being disengaged from the elevator. A slight pull on the control member 11 of the elevator will release the closure 4 and permit the sucker rod to be withdrawn from the elevator, and the withdrawal of the elevator will position the parts again into the position for engaging a second section of the rod.

By this construction the elevator is provided with a closure or latch which automatically locks the rod or casing in the elevator when the elevator is inserted therein and the rod or casing can be released from elevator by gripping the latch control member and exerting a pull on said member in the direction tending to force the rod or casing against the closure, a single pull in one direction releasing the locking means from the closure and withdrawing the elevator from the rod or casing.

I claim:

1. A rod elevator comprising a body having a rod receiving way, a closure for the rear of the way, a dog engaging the closure to yieldingly maintain the closure across the way in open position, a control member for withdrawing the dog from the closure, means at the rear of the closure to form a positive locking engagement with said dog in the closed position, and a shiftably mounted control member operative to move the dog from the locked position.

2. A rod elevator comprising a body having a receiving way, a closure member for the way, a dog, spring means yieldingly

urging the dog against the closure member, and a control member for withdrawing the dog from the closure member, said member being shiftable in a direction tending to pull the elevator away from the rod.

3. A sucker rod elevator comprising a body having a receiving way, a pivotally mounted closure member having two arms defining a receiving way intersecting the 10 first way, one arm closing the first way in the closed position and the other arm extending into the first way in the open position to engage a sucker rod inserted therein and pivot the second member across the way, 15 a dog yieldingly urged against the closure member to yieldingly maintain the member in the open position and engaging a recess in said member to lock the member in the closed position, and a control member slid- 20 ably mounted by the body and operative to

withdraw the dog and release the closure member.

4. An elevator for casing, sucker rods or the like, comprising a body having a receiving way, a closure for the way, means extending into the closure way to engage a sucker rod inserted therein and automatically move the closure across the way, an automatic latch for locking the closure in the closed position, and a reciprocating latch 25 control member operative to release the latch and providing a grip extending to the rear of the receiving way, whereby the latch may be released from the closure by a force applied to the grip tending to pull the elevator away through a rod therein.

Signed at Oxnard, California, this 8th day of June, 1923.

WILLIAM P. SCHLINGER.
